FASTENING PULLING MACHINE

Rouel R. Campbell, Lynn, Mass., assignor to
United Shoe Machinery Corporation, Flemington, N. J., a corporation of New Jersey

Application April 8, 1942, Serial No. 438,131

8 Claims. (Cl. 12—16)

This invention relates to fastening pulling machines, and is herein illustrated as embodied in a machine for pulling tacks from shoes.

In various shoemaking operations tacks are used to hold shoe parts upon a last. For example, insoles are temporarily secured to the bottoms of lasts by means of tacks, which are driven into the last usually until the heads of the tacks are flush with the outer surface of the insole. Machines heretofore provided for removing such tacks, after the shoe has been lasted and other operations performed upon it, usually comprise a rapidly moving tack pulling tool, ordinarily in the form of a claw moving in an orbital path. While such machines have been in successful commercial use for many years, it has been found that under some conditions, such, for example, as where the tacks are driven so deeply into the work that their heads are embedded in the material of the insole, difficulty has been experienced in removing such tacks without damaging the insole. Moreover, in operating such machines without the use of special guards, not only has considerable inconvenience been experienced due to flung tacks, but there is a substantial danger that such flung tacks may injure the operator. In view of the foregoing, it is an object of the invention to provide an improved fastening pulling machine which will be especially adapted for pulling deeply embedded fastenings without injuring the material and which, at the same time, is so constructed as to eliminate likelihood of injury to the operator.

To this end and as illustrated, the invention comprises an oscillating tack pulling tool, having wedge-shaped pulling members so constructed as to cause them to engage the underside of the head of a fastening upon movement of the tool in one direction without danger of damaging the work, and a claw arranged to engage the head of the fastening upon movement of the tool in the opposite direction to ensure removal of the fastening in the return movement of the tool. Preferably each fastening, as it is pulled, is thrown in such a direction as to avoid any possibility of injuring the operator.

These and other features of the invention are disclosed in the following specification, and in the accompanying drawing, and are pointed out in the claims.

In the drawing.

Fig. 1 is a view in side elevation, partly in section, of a portion of a fastening pulling machine embodying the invention;

Fig. 2 is an end view, partly in section, of a

portion of the mechanism for oscillating the fastening pulling tool;

Fig. 3 is an end view, partly in section, illustrating initial engagement of the tool with the work;

Fig. 4 is an end view, partly in section, showing the tool in engagement with the work just prior to a fastening pulling movement of the tool;

Fig. 5 is a vertical cross section through the tool and work, taken along line V—V of Fig. 4; and

Fig. 6 is an end view, partly in section, showing a position of the tool during removal of a fastening from the work.

The illustrative machine is a tack pulling machine which, as shown in Fig. 1, comprises a frame 10 having a projecting arm 12, in which is positioned a shaft 14 carrying at its outer end a tack pulling tool 16. The shaft 14 is oscillated through about 60° by means of a shaft 18 driven by a pulley 20 and carrying an eccentric block 22, slidably positioned in a slot 24 in an arm 26 secured by a bolt 28 to the inner end of the shaft 14.

The tool 16, in the construction herein shown, comprises two plates 30 mounted upon a stud 32 in the outer end of the shaft 14, and held in position thereon by a nut 34 and a key 36. The plates 30 are cut away at the lower ends thereof to form a passage and terminate in a flange 38, end portions of which are tapered to form a wedge 40. The flanges 38 are spaced apart to form a slot 42, Fig. 1, constituting a passage extending entirely through the tool and along which tacks may pass as they engage the tool and after they have been removed from the work.

The shape of the wedge portions 40 of the flanges 38 is such that, as the tool is moved over the work, such as the bottom of a lasted shoe 44, the edge portions of the flanges will depress the material adjacent to a tack, such as tack 46, to be removed from the work, and enter beneath the head thereof, engaging the underside of the head and raising the tack slightly out of the work.

In order to pull the tack from the work upon the return movement of the tool, there is provided a claw 48, Figs. 3, 4 and 6, mounted upon a pivot 50 near the edge portions of the plates 30. The claw normally extends across the space between the plates and rests upon the upper portions of the wedges 40. When the tool is moved in one direction, the claw is pushed upwardly by the head of the tack, and then drops down into engagement with the upper surfaces of the wedge portions 40. Upon return movement of the tool, the edge of the claw will engage the

underside of the head of the tack, as shown in Fig. 4, and upon continued movement of the tool will pull the tack from the work, as shown in Fig. 6.

The speed of the tool is about 1200 oscillations per minute. At this speed, the velocity of a tack, after it has been removed from the work, will be such that upon the next advance movement of the tool, subsequent to pulling the tack, the tack will be thrown away from the tool, passing out at the rear end of the slot 42.

In the operation of the machine, the operator stands beyond the outer end of the shaft 14 and the tool 16, and advances a shoe, such as shoe 44, past the tool from right to left in Figs. 3, 4 and 6. The tacks removed will be thrown to the operator's left, thus eliminating any likelihood of injury to the operator, due to flying tacks. Because of the wedge shape of the claw members 38, the removal of deeply embedded fastenings is facilitated; it only being necessary for the operator to tilt the shoe and force the same against the tool until the wedge members engage the underside of the head of the tack.

Having described my invention, what I claim as new and desire to secure by Letters Patent of the United States is:

1. In a fastening pulling machine, a pulling tool having a pair of spaced wedges adapted to engage the underside of the head of a fastening to be pulled, a claw normally in engagement with the wedges, and means pivotally mounting the claw for movement away from the wedges under action of a fastening initially engaged by the wedges.

2. A fastening pulling machine comprising an oscillating tool having a slot extending from one end thereof to the other to embrace the head of a tack to be pulled upon movement of the tool in one direction, and a claw mounted upon the tool and movable into position back of the head of the tack to pull the tack from the work upon movement of the tool in the other direction.

3. In a fastening pulling machine, a pulling tool comprising a plurality of spaced members having flanges each terminating in a wedge, a claw positioned between the members and pivotally mounted thereon for movement toward and away from the flanges, and means for oscillating the tool.

4. In a fastening pulling machine, a pulling tool comprising a plurality of spaced plates having depending portions terminating in inwardly extending flanges providing a passage for fastenings which extends from one end of the tool

to the other, a claw positioned between the plates and pivotally mounted thereon for movement toward and away from the flanges, and means for oscillating the tool.

5. In a fastening pulling machine, a pulling tool comprising a pair of spaced members having depending portions terminating in flanges spaced apart to form a passage for fastenings, each of the flanges having at an end thereof a wedge-shaped portion adapted to enter between the head of a fastening to be pulled and the work in which it is embedded, a claw pivotally mounted for movement toward and away from the flanges adjacent to the wedge portions thereof, and means for oscillating the tool to cause a fastening positioned in the passage to be gripped between the wedge portions of the flanges and the claw and thereafter to remove the fastening from the work.

6. In a fastening pulling machine, a pulling tool comprising a pair of spaced members each having laterally extending flanges spaced apart to form a passage for fastenings extending through the tool, said flanges terminating in wedge-shaped portions constructed and arranged to engage the underside of the head of a fastening to be pulled, a claw normally extending in engagement with the flanges and pivotally mounted for movement away from the flanges under the action of a fastening upon entering the passage, and means for oscillating the tool.

7. In a fastening pulling machine, a pulling tool comprising a plurality of spaced members terminating in flanges spaced apart to form a passage for fastenings, the flanges having their portions constructed and arranged to enter between the head of a fastening to be pulled and the work in which it is embedded, and a claw pivotally mounted upon the members for movement away from the flanges during movement of the tool in which a fastening is presented to the passage and to engage the fastening upon movement of the tool in the opposite direction.

8. In a fastening pulling machine, an oscillating shaft, a tool mounted upon the shaft comprising two spaced plates having inturned flanges forming therebetween a passage for fastenings and each terminating in wedge-shaped end portions constructed and arranged to engage the underside of the head of a fastening to be pulled, and a claw pivotally mounted upon the tool and normally extending into engagement with the wedge-shaped end-portions of the flanges.
